DOUBLE HUNG WINDOW SASH AND FRAME CONSTRUCTION

Edwin Moll, Portland, Oreg.

Application September 20, 1932, Serial No. 633,986

2 Claims. (Cl. 16—197)

My invention relates to window frames and sashes. It is particularly adapted for use upon what is known to the trade as double hung sashes, each of which is adapted for being moved in a vertical plane within definite guideways.

Heretofore, it has been the general custom in window frames and sashes of this kind to balance the windows through the use of cords, pulleys and counterweights. This is not only expensive but requires time to install and expense in the materials used in this class of construction. This form of construction also has the disadvantage of the final wearing of the cord to destruction which requires the dismantling of the entire frame to re-establish the counterweights.

Through the use of my new and improved construction I dispense entirely with counter-weights as commonly used in window construction and secure a suitable chain at its opposite ends to the respective side walls of the sash whereby the windows themselves function as counter-weights, and I further provide a yieldingly mounted pulley for the chain for taking up the counter balancing weight required to facilitate the easy movement.

I also provide, in my construction, the essential elements for maintaining the sashes in an air-tight condition relative to the frames to thereby eliminate the necessity of weather stripping.

One of the primary objects of my invention is to provide a simplified construction for use upon double hung windows.

A still further object of my invention consists in providing means for supporting and maintaining double hung windows within their frames, at less expense.

A still further object of my invention consists in providing a double hung window and frame assembly that may be assembled with the expenditure of less labor than has heretofore been accomplished.

And a still further object of my invention consists in the development of a double hung window and frame, that can be made relatively air-tight at the time of assembly, to thereby eliminate the necessity of weather stripping the same.

A still further object of my invention consists in so constructing a double hung window and frame assembly that it will have a long, useful life and one that is practically free from operating mechanical annoyances.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a front view of a double hung window

comprised of an upper and a lower sash, each sash being shown in its normal raised and lowered position.

Fig. 2 is a front view of a double hung window illustrating the upper sash as being in full raised position and the lower sash as being in a partially raised position.

Fig. 3 is a front view of a double hung sash window illustrating the upper sash as being partially lowered and the lower sash as being partially raised.

Fig. 4 is a fragmentary, sectional, side view of the sash and frame. This view is taken on line 4—4 of Fig. 10, looking in the direction indicated.

Fig. 5 is a perspective, side view of one of the end fasteners adapted for being raised and lowered into the groove and to which the supporting chain or cord is secured upon its one end.

Fig. 6 is a sectional, end view, of the sash, the guideways and of the frame. This view is taken on line 6—6 of Fig. 4, looking in the direction indicated.

Fig. 7 is a fragmentary, sectional, end view of the mechanism illustrated in Fig. 4. This view is taken on line 7—7 of Fig. 4, looking in the direction indicated.

Fig. 8 is a fragmentary, sectional, side view of the mechanism illustrated in Fig. 10. This view is taken on line 8—8 of Fig. 10, looking in the direction indicated.

Fig. 9 is a fragmentary, sectional, end view, of the sash and guide strip associated therewith and of the frame.

Fig. 10 is a sectional, side view, of the assembled frame and sash illustrating the top sash as being partially lowered and the lower sash as being partially raised. This view is taken on line 10—10 of Fig. 3, looking in the direction indicated.

Fig. 11 is a sectional, side view of the sash and frame illustrating the top and bottom sash as being fully raised and fully lowered. This view is taken on line 11—11 of Fig. 1, looking in the direction indicated.

Fig. 12 is a sectional, side view of the sash and frame, illustrating the top sash raised and the lower sash partially raised. This view is taken on line 12—12 of Fig. 2, looking in the direction indicated.

Like reference characters refer to like parts throughout the several views.

1 is the sill of the window frame. 2 is the cap of the window frame. 3 and 4 are the window frame posts. 5 is the top sash of the window and 6 is the bottom sash of the window.

I cut out portions of the posts 3 and 4 to form parallelly disposed grooves, here shown as two in number, and illustrated at 7 and 8. The grooves are in alignment with the post engaging faces.

of each of the sash members. This leaves a dividing strip 9 that runs longitudinally of the sash engaging face of each of the posts. A T-shaped strip 10 is secured to the outer face 5 of each of the dividing strips with the head ends 11 and 12 of the T-shaped strip extending outwardly from the dividing strip, to partially close the grooves 7 and 8 that are disposed at the oppositely disposed sides of the dividing strip 9.

10 I provide sufficient clearance between the shank 13 of the T-shaped strip and the sashes to allow their free movement up and down.

I also place strips, preferably made of hard- 15 wood as illustrated at 14 and 15 in each of the outer edges of each of the sashes and permit the same to extend within the grooves and to entirely fill the space between the T-shaped strip and the faces 16 and 17 of the respective grooves 7 and 8.

20 I also place a groove 18 in the top cross member of the top sash and I place a strip of material 19 within the cap 2, so that a relatively air-tight connection may be formed between the top sash and the frame when the top sash is fully raised.

25 I form a groove 20 in the top side of the sill and place a window strip 21 within the groove. The window strip is in alignment with a slot 22 formed in the bottom of the lower sash to render the same relatively air-tight when the bottom

30 sash is fully lowered and the window strip is projected into the slot 22.

An eye bolt is secured to the top plate, having a coil spring 24 secured thereto. The oppositely disposed end of the coil spring is secured to the 35 yoke 25. The yoke 25 has a pulley 26 journaled relative thereto and about which a chain or cord 27 is trained. One end of the cord is fixedly secured to the lower end of the bottom sash and the oppositely disposed end of the chain or cord 40 is secured to the bottom side of the upper sash. Similar chain, pulley and spring assemblies are disposed at each side of the window casing.

To facilitate the fastening of the chain to the 45 respective sash members, I provide a fastening, as illustrated in Fig. 5. This member is preferably made of sheet metal folded upon itself to form parallelly disposed side walls 28 and 29. Fastening teeth 30 and 31 are formed integral with the respective side members 28 and 29.

50 These locking teeth are preferably disposed substantially at the bottom end of each of the side wall members and are flared outward, as illustrated in Fig. 9. The outside spacing of the side walls 28 and 29 are made to substantially fill the 55 space disposed between the outer ends of the heads 11 and 12 of the T-shaped member 10 and the inner surfaces 16 and 17 of the grooves disposed longitudinally of the inner surface of the post.

60 The supporting member is inserted within the slot and driven in until it occupies the dotted position, as illustrated in Fig. 8.

A means for attaching the chain or chord is 65 formed within the U-shaped portion of the fastening member and is illustrated in Fig. 5 at 32. In order to maintain an air-tight relationship within the slots I secure a felt or other compressible member 33 to the body of the device, as illustrated in Fig. 5, which is of substantially 70 the same size as a horizontal section of the groove and forms an air-tight stop within the grooves 7 and 8. The yoke 25 is adapted to be vertically moved through a slot 34 disposed within the respective posts. The pulley 26 is journaled 75 about the leg 36 of the yoke 25. A shroud for

the pulley is formed by securing a pair of ears to the upper leg of the yoke 25 and permitting them to straddle the pulley as the legs of a pulley block would, assuming the leg 36 to be the pulley shaft. A closure plate 38 is carried by 5 the yoke and is adapted to engage the outer surface of the post of the window frame and to close the slot 34.

The respective plates disposed upon the oppositely disposed outer surfaces of the post are 10 floated upon the yokes and when the upper and lower sashes are in their normal raised and lowered position the floated plates close the slot 34.

When the assembly is complete a normal tension is placed within the respective springs disposed at the oppositely disposed sides of the 15 frame to absorb practically the total weight of the respective sashes. This facilitates the raising and the lowering of the respective sashes.

Upon the partial raising of the lower sash, as 20 illustrated in Fig. 2, the upper sash will remain closed until the yoke 25 reaches the top of the slot 34. Upon the further raising of the lower sash the top sash will be lowered automatically so that the respective sashes will 25 occupy the position as illustrated in Fig. 3. Upon the complete lowering of the lower sash the upper sash will be automatically raised to closed position.

While I have here shown in the drawings an 30 opening having a wooden frame disposed thereto and into which wooden sash have been fitted I do not wish to be limited to the adaptation of my new and improved construction to wood as 35 the same principle may be adapted to metal construction with equal facility.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. The combination with a window frame and an upper and a lower sash slideable within the frame, of fastening means secured to the post engaging edges of each sash, flexible lifting members secured at their ends to the fastening means, 50 resilient members secured to the window frame, a pulley supporting yoke secured to the depending end of each of the resilient members, said yoke extending through a slot in the window post, a pulley mounted upon the yoke and the above mentioned flexible lifting members trained about the pulley.

2. The combination with a window frame and an upper and a lower sash slideable within the frame, of fastening means secured to the lower 60 extremity of each of the window post engaging edges of the sash, reacting elements secured to the upper cross member of the window frame and contained within the frame, a pulley supporting yoke secured to the depending end of each reacting element, said yoke extending through a slot in the window post, a pulley secured to the outwardly protruding portion of the yoke and adapted for vertical movement within a groove 65 in the outer face of the window post and flexible lifting members secured at their ends to the above mentioned fastening means and trained about the respective pulleys.
